LATCHING DEVICE

Carl Lomholt, Bogota, N. J., assignor to Federal Telephone and Radio Corporation, New York, N. Y., a corporation of Delaware

Application May 17, 1946, Serial No. 670,568

7 Claims. (Cl. 74—536)

1

The present invention relates to latching devices and particularly to latching devices for use in multiposition switching keys such as those commonly used in the telephone art.

More particularly still the device of this invention is designed to be utilized as an attachment for any one of a large number of specifically different switching keys of the telephone type.

It is an object of the invention to provide an improved latching device for switching keys of the lever type or in other words a device for locking a telephone type key lever switch in any one of its plurality of positions.

It is another object of the invention to provide such a latching device which will permit ready operation of the key lever from one position to another and which will hold the key lever positively in any adjusted position.

It is a further object of the invention to provide such a key lever latching attachment which may be easily operated with one hand.

It is a still further object of the invention to provide such a latching device which may be readily installed on a key lever switch and which is simply and economically manufactured.

Other objects and features of the invention will appear when the following description is considered in connection with the annexed drawing, in which—

Figure 1 is a central cross sectional view of the latching device of the present invention showing its application to a standard form of telephone switching key;

Figure 2 is an end elevation of the key of Figure 1; and

Figure 3 is a top plan view showing the arcuate latching plate which cooperates with the latching device of Figures 1 and 2.

Referring now to Fig. 1, there is shown at 10 the switch plate of a normal telephone type key lever switch, this plate being mounted on the framework 11 which is in turn supported in any suitable manner, as, for example, by internally threaded studs 12 riveted to framework 11. The pivoted operating or key lever 13 is pivoted at the point 13a in the usual manner and terminates in a threaded shank 14. In the normal key not supplied with my latching device a handle of any suitable material is threaded on the shank 14.

The latching device of my invention comprises a tubular body member 15 which may be made of metal and which is provided with two downwardly extending latching projections 16. Body member 15 is provided with a rectangular cut-out 19 which cooperates with the latching plate of

2

Figure 3 in a manner which will be hereinafter described. The exterior diameter of the upper portion of the member 15 is reduced and forms a seat for a sleeve 17 of suitable material as, for example, Bakelite. Knob 18 which may also be of Bakelite screws into an internal thread in the upper portion of the body member 15 and thus holds sleeve 17 in place on its seat. If desirable the sleeve 17 and knob 18 may be integral.

10 The body portion 15 is also recessed as indicated at 20 providing a space in which a coil spring 21 is compressed, the upper portion of the spring 21 resting against the head of an internally threaded sleeve 22 which sleeve is threaded onto the shank 14. The exterior surface of sleeve 22 forms a bearing for the interior bore of the body member 15.

15 Mounted on the switch plate 10 in any suitable manner as, for example, by means of the screws 20 23 is a member 24 which comprises the upstanding arcuate plates 25 which lie within the cut-out 19 and guide the key lever 13 in its pivotal movement. Each of the arcuate plates 25 has a plurality of latching lugs 26 bent therefrom and 25 lying in generally horizontal planes as seen in the drawing. The latching projections 16 of the device cooperate with the latching lugs 26 to hold the switch in any position in which it is set.

20 As will be clear when it is desired to install the 30 device of my invention on a key switch the usual handle is removed from such switch and the body member 15 slid over the shank 14 of the key lever 13. The spring 21 is next inserted in the recess 25 and the threaded sleeve 22 is then screwed into 35 the shank. Next, sleeve 17 is inserted over the exterior of the body member 15 and the knob 18 40 screwed into position with its external threads meeting with the internal threads in the body portion 15, thus completing the assemblage and causing the body member and the latching lug carried thereby to be pressed downwardly as seen in the drawing.

45 When it is desired to operate the switch the sleeve 17 or handle 18 is grasped in the fingers 45 and moved upwardly compressing the spring 21 and causing disengagement of the projections 16 of the body member 15 from the lugs 26. Thereupon, the key lever 13 is pivoted about the point 13a to its desired position and the handle then 50 released whereupon spring 21 causes the downward projections 16 to again engage against the lugs 26 to hold the switch lever in its new position.

55 While I have described a preferred embodiment of my invention it will be understood that

other forms may be devised without departing from the scope of the invention and, therefore, I do not desire to be restricted to the particular details shown and described but only within the scope of the appended claims.

What is claimed is:

1. A latching device for attachment to a key lever switch, said device comprising, in combination, a latching member having arcuate upstanding arms mounted on the switch face plate with said arms extending one on either side of the key lever and parallel to its path of movement, a plurality of latching lugs on each of said upstanding arm, a body member mounted on the key lever and having a cut-out portion fitting over said upstanding arms, latching projections on said body member for engaging said latching lugs and spring means urging said body member toward said latching lugs and into engagement therewith.

2. A latching device for attachment to a key lever switch, said device comprising, in combination, a latching member having arcuate upstanding arms mounted on the switch face plate and extending one on either side of the key lever and parallel to its path of movement, a plurality of latching lugs on each said upstanding arm, a body member mounted on the key lever and having a cut-out portion fitting over said upstanding arms, latching projections on said body member for engaging said latching lugs, spring means urging said body member toward said latching lugs and into engagement therewith, and a handle member connected to said body member.

3. A latching device for attachment to a key lever switch, said device comprising, in combination, a latching member having arcuate upstanding arms mounted on the switch face plate and extending one on either side of the key lever and parallel to its path of movement, a plurality of latching lugs on each said upstanding arm, a body member mounted on the key lever and having a cut-out portion fitting over said upstanding arms, latching projections on said body member for engaging said latching lugs, spring means urging said body member toward said latching lugs, a sleeve mounted on said body member, and an operating handle fixed to said body member and holding said sleeve in position thereon.

4. A latching device for attachment to a key lever switch comprising, in combination, a plate having latching means mounted adjacent the face plate of the switch, an internally threaded sleeve mounted on the switch key lever, a body member slidably mounted on said sleeve, said body member having a projection for cooperation with said latching means and resilient means mounted in

a recess of said body member and between said body member and said sleeve for urging said body member into position with said projection in engagement with said latching means.

5. A latching device for attachment to a key lever switch comprising, in combination, a plate having latching means mounted adjacent the face plate of the switch, an internally threaded sleeve mounted on the switch key lever, said sleeve having a head, a body member slidably mounted on said sleeve, said body member having means for cooperation with said latching plate and resilient means mounted in a recess of said body member and extending between a shoulder of said body member and the head of said sleeve.

6. A latching device for attachment to a key lever switch comprising, in combination, a plate having latching means mounted adjacent the face plate of the switch, an internally threaded sleeve mounted on the switch key lever, said sleeve having a head, a tubular body member slidably mounted on said sleeve, said body member having means for cooperation with said latching plate and resilient means mounted in a recess of said body member and extending between a shoulder of said body member and the head of said sleeve.

7. A latching device for attachment to a key lever switch comprising, in combination, a plate having latching means mounted adjacent the face plate of the switch, an internally threaded sleeve mounted on the switch key lever, said sleeve having a head, a body member slidably mounted on said sleeve, said body member having means for cooperation with said latching plate, resilient means mounted in a recess of said body member and extending between a shoulder of said body member and the head of said sleeve, and a handle member fixed to said body member whereby said body member may be moved out of engagement with said latching means to permit movement of the key lever to any of its plurality of positions, said resilient means returning said body member to latching position upon release of said handle.

CARL LOMHOLT.
